UNITED STATES PATENT OFFICE

ALBERT T. GOFF, OF MONTOOOTH BOROUGH, PENNSYLVANIA.

MACHINE FOR LOADING COAL FROM THE TIPPLES INTO CARS.

No. 820,565.

Specification of Letters Patent.

Patented May 15, 1906.

Application filed January 4, 1905. Serial No. 239,678.

To all whom it may concern:

Be it known that I, ALBERT T. GOFF, a citizen of the borough of Montooth, in the county of Allegheny, State of Pennsylvania, have invented a new and useful Machine for Loading Coal from the Tipple into Cars, of which the following is a specification.

This invention relates to improvements in chutes for use in coal-tipples for loading coal from the weighing-pan into railway-cars.

The object of the invention is to provide a simple, durable, and efficient device of this character by means of which coal may be loaded in an expeditious and economical manner.

With the above and other objects in view my invention consists in the novel construction illustrated in the accompanying drawings, in which—

20 Figure 1 is a view of one end of the upper section of my improved two-part chute. Fig. 2 is a side elevation of the same. Fig. 3 is a view of the opposite end of the same. Fig. 4 is a view of the small end of the lower section 25 of the two-part chute. Fig. 5 is a side elevation of the lower chute-section. Fig. 6 is a view of the large end of the lower chute-section. Fig. 7 is a side elevation of my improved two-part chute, showing its lower section 30 in its lowered position. Fig. 8 is a view similar to Fig. 7, showing the lower chute-section in its elevated position. Fig. 9 is a detail vertical sectional view through a portion of a coal-tipple, showing the manner in 35 which my improved single chute is mounted, the latter being in side elevation. Fig. 10 is a vertical transverse sectional view taken on the plane indicated by the line 10 10 in Fig. 9. Fig. 11 is a longitudinal sectional view 40 through a portion of a coal-tipple, showing one way in which the improved two-part chute may be suspended and adjusted; and Fig. 12 is a vertical transverse sectional view taken on the plane indicated by the line 12 12 45 in Fig. 11.

Referring more particularly to Figs. 1 to 8, inclusive, of the drawings, in which I have shown an embodiment of my invention consisting of a two-part or two-section chute, the numeral 1 denotes an upper member or section and the numeral 2 a lower member or section, which has one of its ends pivotally connected to one end of the section 1, so that its opposite end may slide vertically upon or 50 telescope the section 1. The upper section 1

5 consists of a substantially rectangular frame 3 of angle metal, to the side portions of which are riveted or otherwise secured sheet-metal sides 4, which taper slightly from one end to the other. These sides are stiffened by metal 60 braces 5, which are secured, as shown, upon their outer faces. The lower section 2 of the chute comprises a substantially rectangular angle-metal frame 6, which is of greater size than the frame 3 and which has secured to it 65 a sheet-metal body portion or chute proper, 7. The latter tapers from one of its ends to the other, as shown, and is strengthened or reinforced by angle-metal braces 8, secured upon its outer faces and to the frame 6, as clearly 70 shown in the drawings. The small end of the chute-section 2 is closed by a segment-shaped head 9 and its opposite large end is open to permit the coal to discharge therefrom into a railway-car, receptacle, or the like. The sec- 75 tion 2 has its small end pivoted, as shown at 10, to the small end of the section 1, so that its large or discharge end may swing in a vertical plane and telescope the sides 4 of said upper section 1. The downwardly-swinging move- 80 ment of the outer or free end of the section 2 is limited by one or more chains 11, which connect the two sections 1 2 at their large ends. The section 2 may be adjusted verti- 85 cally upon the section 1 by drawing upon chains or other flexible connections 12, which have their lower ends attached to the discharge end of the section 2 and their upper ends actuated by any suitable mechanism.

The chute may be mounted and operated 90 in any manner by any suitable mechanism, and in Figs. 11 and 12 of the drawings I show one manner in which this may be done. As there shown the entire chute is suspended 95 from a suitable support 30 in a coal-tipple or the like 31 by four chains, cables, or other flexible connections 32, which have their lower ends attached to the four corners of the rectangular frame of the section 1. If desired, these chains or connections 32 may be 100 adjustable, so that the chute may be raised and lowered vertically or horizontally, as may be found necessary or desirable in loading cars. As shown in these figures of the drawings, the outer or free end of the lower 105 section 2 is counterbalanced by weights 33, so that said chute-section may be adjusted at any angular position within the range of the chains or connections 11. As shown, these weights 33 are a little heavier than the 110

chute-section 2. They are connected to the ends of cables or the like 34, which pass over pulleys 35, and have their opposite ends connected to the sides of the free or outer end of 5 the chute-section 2, as clearly shown in Fig. 12. The pulleys 35 are secured upon a shaft 36, which is mounted in suitable bearings upon a horizontal frame or support 37, mounted in the coal-tipple. Upon said shaft 10 is also provided a friction-wheel 38, which is engaged by a friction brake-band 39, which has its end attached to the ends or arms of a bell-crank or lever 40, pivotally mounted at 15 41 upon the frame or support 37. One of the arms of the bell-crank or lever 40 is extended and has adjustably mounted upon it a weight 20 42, which is adapted to normally hold the brake-band 39 in frictional engagement with the wheel 8, so as to prevent rotation of the same, and hence the shaft 36. This brake may be released by drawing upon a cord or cable 43, one end of which hangs within convenient reach of a person upon a car beneath the chute and the other end of which is 25 passed over a guide-pulley 44 and is attached to the weighted end of the lever or bell-crank. When the cord or cable 43 is drawn upon, the shaft 36 is released, so that the weights 33 can descend and elevate the chute-section 2, 30 so that the latter may be drawn or swung downwardly and retained in an adjusted position as soon as the cord or cable 43 is released. It will be understood that instead of employing this counterbalanced device for 35 the chute-section 2 differential chain-blocks or other devices may be provided for accomplishing the same purpose.

The embodiment of my invention (shown in Figs. 9 and 10 of the drawings) comprises a 40 chute 20, which is in all respects similar to the member or section 2 of the two-part chute previously described. This chute 20 instead of being pivoted and suspended by means of chains is mounted on wheels or 45 rollers 21, which run upon a horizontal frame 22, suspended by means of hanger-rods 23 in the coal-tipple. The track-frame 22 is rectangular in form, and the wheels 21 are flanged to engage its rectangular side beams, 50 as clearly shown in Fig. 10. By mounting the chute 20 in this manner it may be shifted longitudinally beneath the usual weighing-pan 30, so that the railway-car 31 will be properly trimmed while being loaded.

55 The use and many advantages of the invention will be readily understood from the foregoing description, taken in connection with the accompanying drawings. It will be seen that by means of the invention coal may 60 be loaded upon cars in a regular and uniform manner, so that there will be little or no breakage. The chute receives the coal from the right-angularly-extending weighing pan or box, checks its downward movement, and 65 deposits it longitudinally in the center of

the car, thereby properly distributing the coal and permitting the car to be readily trimmed, so that there will be little or no loss in transportation.

Various changes in the form, proportion, 70 and the minor details of construction may be resorted to without departing from the principle or sacrificing any of the advantages of this invention.

Having thus described my invention, what 75 I claim, and desire to secure by Letters Patent, is—

1. A chute comprising a substantially rectangular angle-metal frame, a longitudinally-tapered sheet-metal body of substantially 80 semiconical form in cross-section secured upon said rectangular frame, angle-metal brace-bars secured upon the outer face of said body and to said frame, said braces being arranged at the ends of said body and at 85 intermediate points, a substantially semicircular head closing the small end to said body, and means for suspending said body.

2. A chute comprising upper and lower 90 pivotally-connected telescoping sections, said upper section consisting of a frame and sides carried thereby, and said lower section consisting of a frame and a tapered body carried by said frame, and means for suspending said chute.

95 3. A chute comprising upper and lower pivotally-connected sections, the upper section consisting of a rectangular frame and longitudinally-tapered depending parallel sides, and the lower section consisting of 100 a rectangular frame pivoted at one end to one end of the upper section, a longitudinally-tapered substantially semiconical body, means for limiting the swinging movement of said lower section, and means for suspending 105 said upper section.

4. A chute comprising upper and lower telescoping sections pivoted together at one end, said upper section consisting of a frame and depending sides, and said lower section 110 consisting of a frame and a body having an inclined bottom, flexible connection between the free ends of said sections to limit the downward swinging movement of the lower section, and means for suspending said upper 115 section.

5. The combination with a suitable support and a substantially rectangular horizontally-disposed track-frame suspended therefrom, of a chute comprising a substantially rectangular angle-metal frame, a longitudinally-tapered sheet-metal body of substantially semiconical form in cross-section secured upon said rectangular frame, angle-metal brace-bars secured upon the 120 outer face of said body and to the said frame, said braces being arranged at the ends of said body and at intermediate points, a substantially semicircular head closing the small end of said body, and supporting- 125 130

wheels upon said chute adapted to run upon said track-frame, substantially as shown and described.

6. The combination with a suitable support of a chute comprising upper and lower telescoping sections pivotally connected at one end, said upper section consisting of a frame and depending sides and said lower section consisting of a frame and a body having an inclined bottom, a connection between the frame of the upper section and said support for supporting the chute, a flexible connection between said sections for limiting the swinging movement of the lower section, and means for supporting said lower section in an adjusted position. 15
